UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK.

TELEPHONE-EXCHANGE SYSTEM.

1,107,148.

Specification of Letters Patent.

Patented Aug. 11, 1914.

Application filed August 1, 1906. Serial No. 328,723.

To all whom it may concern:

Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.

10 My invention relates to telephone exchange systems and has for its object the production of such a system in which the calls originating at subscribers' stations are distributed among connective terminals such 15 as operators' plugs, in an improved manner.

Briefly stated, my invention comprises connective apparatus, which may be either manual or automatic as regards the calling part thereof, and which is provided with 20 what I have called relay primary selectors, as described in the above mentioned application, for the purpose of answering incoming calls and connecting the calling lines to idle trunks or connective circuits. These relays 25 are arranged so that they bear a decimal relation to each other and to the lines, and they are positive in their action, being controlled by the calling lines themselves.

In operation, when a line calls, its line relay pulls up, closing the circuit of the appropriate tens and units relays of that hundreds group to which the calling line belongs, and these two relays in pulling up connect the line onto the trunk with which 35 they are associated. Such connection being complete, the conditions are the same as if an operator had manually inserted a plug into the ordinary answering jack of the calling line; and the sleeve or other relays of 40 the trunk, as well as the cut-off relay of the line, immediately take current and perform their usual functions. The primary selector relays are self-locking, and the locking circuit for each trunk group is controlled by 45 one of the distinctive trunk relays which responds to acts of the subscriber, whereby at the conclusion of the conversation, when the subscriber hangs up his receiver, the locking circuit is broken and the primary 50 selector relays let go, disconnecting the line from the trunk in the same manner as if an operator had pulled out an answering plug which had previously been inserted.

In the present application I have specifically illustrated, and shall hereinafter spe-

cifically describe and claim, primary selector relays applied to trunks leading into automatic switch circuits, the trunks themselves being controlled by operators, who manipulate the automatic switches in order to effect connection with the wanted lines as they are called for. In order to enable the operators to conveniently control the switches I provide each operator with a plurality of push button keys somewhat similar to those used in computing machines, these keys serving to connect a power driven impulse transmitter or transmitters to the respective trunks as they come into use and according to the numbers wanted.

This description is accompanied by ten figures, in which—

Figure 1 shows substation telephone equipments; Figs. 2, 3 and 4 show relays involved in a system of automatic call distribution; Fig. 5 shows manual connecting units; Fig. 6 shows a selective impulse sending device; Fig. 7 shows an automatic switch or connector; Fig. 8 shows the scheme of the connecting relays of Figs. 2, 3 and 4; 80 and Figs. 9 and 10 show detail of a relay having a large number of contacts. Figs. 1 to 7 may be arranged to form one large diagram of the system of my invention.

That portion of my system which is illustrated in Figs. 2, 3 and 4 constitutes what I have termed the primary selector or answering portion of the system. In this, as already set forth, appear a number of ten point relays and a number of single point 90 or ordinary relays. These latter may be of any suitable type. The only special feature required is that of double winding, which, as I shall point out hereinafter, can be dispensed with if some other means be provided 95 for locking the relays when energized. The apparatus at the subscribers' stations also forms no part in itself of my present invention, except as it co-acts with the apparatus and circuits at the central office. I contemplate using an ordinary common battery 100 telephone outfit the same as those employed in standard manual switchboard systems.

Referring then to Figs. 9 and 10, I will briefly describe the ten point relay, N. This 105 comprises an iron back yoke, n, a pair of magnets, n', mounted thereon, an armature, n², extending across the front end thereof, and a set of contact-springs, n³, n⁴, n⁵, n⁶, overlying the upper bell-crank extension of 110

the armature, so as to be worked thereby. There are eleven sets of these springs, all secured at the rear end of the relay upon the return member, n^7 , of the back yoke. 5 The front ends or pole pieces of the cores of the electro-magnets, n^1 , receive the front yoke, n^8 , of nonmagnetic material, such as brass, this also having an upper return portion, n^9 , overlying the magnet windings, and 10 alined with the return portion, n^7 , of the back yoke, n^1 . Upon this return portion, n^9 , of the front yoke the upper bell-crank arm, n^{12} of the armature, n^2 , lies flat under normal conditions. Cut from end to end of 15 this upper bell-crank portion, n^{12} , are two grooves in which rest the insulating studs of the spring sets. The function of these slots with the studs resting in them is to retain the armature in place. At their front 20 ends the springs are separated by shouldered studs, the lowermost stud of each pair resting upon the armature, carrying the lower spring of its pair, n^6 , on its shoulder, and the upper spring, n^5 , on its head, its stem 25 passing through a hole in the spring, n^6 , while the uppermost stud of each pair rests upon the spring, n^5 , supports the spring, n^4 , upon its shoulder, and carries the spring, n^3 , on its head, its stem passing through a hole 30 in the spring, n^4 . The actuating studs affect only the springs, n^4 , n^6 , of each set, those constituting the movable springs, while the others, n^3 , n^5 , are fixed. Each actuating stud carries the spring, n^6 , on its shoulder, 35 and the spring, n^4 , on its head, its stem passing through holes in the springs, n^5 , n^6 . The entire relay is secured to an insulating back block, n^{10} , by means of the bolts, n^{11} , constituting extensions of the cores and 40 threaded to receive lock-nuts. The rear ends of the contact-springs extend out through openings made in this block, and an inclosing shell or casing, n^{13} , is fitted to the block, with which it forms a tight joint all around 45 the edge. This shell is secured in place by means of the stud, n^{14} , threaded to receive the nuts, n^{15} . As the armature, n^2 , is attracted, the springs, n^4 , n^6 , are lifted by the actuating stud, until their outer points make 50 contact with the corresponding points of the springs, n^3 , n^5 , in each set. Ten of these sets are line-contacts, and the eleventh is for locking purposes, as will sufficiently appear from the description of the circuits. 55 Following is a description of the circuits, beginning with Fig. 1. Therein I have shown three subscribers' stations, A, A', A'', each equipped with a telephone transmitter, a receiver, a switch-hook, a ringer, and condenser, all of usual or suitable type for use with common battery circuits. When the hook is up, that is when it is relieved of the weight of the receiver, the circuit is through the transmitter and receiver; and when the 60 hook is down, the line-circuit is completed. 65

for alternating current only, through the ringer and condenser. Since the circuits are the same for all the lines, I will refer to the line from station A² only. This consists of conductors 1 and 2, extending from the substation to the central office. At the substation the talking circuit is completed through the wires 3—4 when the hook is up, and the ringing circuit through the wires 5—6 when the hook is down. These figures are useful 70 for the purpose of tracing the circuits only. 75

Turning now to Fig. 2, the line-wires 1 and 2 appear at the left hand side of the figure, terminating in contacts of the cut-off relays M', which are normally deenergized, so that in each case the line-wire 2 is grounded at 7 and the line-wire 1 extended through line 8 to the line-relay M, and so to main battery B and ground. The armature, m , of each line-relay M is grounded at 9, 80 and when attracted is adapted to close upon terminal contacts of wires leading to the tens and units relays of the primary selector sets. I preferably divide all the incoming lines in an exchange into groups of 85 say one hundred each, and to each group I apportion a fixed number of trunks leading to connective apparatus. In a small or comparatively inactive exchange the percentage of these trunks may be as low as five, and 90 in busy exchanges it may be raised to ten or even fifteen. I assume, however, that ten per cent. of connective apparatus will be sufficient to care for the present system, hence I provide ten trunks for each one 95 hundred lines, and a complete set of tens and units relays in a primary selector group for each trunk. The circuits herein illustrated show six lines, which for convenience I will call No. 500, 501 and 502 (Fig. 2) 100 and 510, 511 and 512 (Fig. 3). The subscribers' circuits of Fig. 1 will fit any of these, and in order to fully comprehend the connections of these lines and the arrangement of the tens and units relays, it is necessary 105 to consider Figs. 2, 3 and 4 together. In Figs. 2 and 3 the subscribers' extension lines are shown coming into their initial terminals on the tens relays, which are of the type shown in Figs. 9 and 10. Each 110 of these relays carries the terminals of ten lines, and for each trunk there are ten of these relays, so that for 100 lines, provided with ten trunks, there will be 100 ten point relays, containing 1,000 line-terminals; from 115 which it appears that each line can be multiplied ten times, which it should be in order to obtain access on occasion to every one of the ten trunks. The contacts on the ten point relays are arranged in duplicate pairs. That is, the incoming lines terminate each on one pair of springs, opposite which another pair of springs appears to which the line is connected when the relay is energized, and from which a local circuit passes 120 125 130

to the front contact springs of a particular units relay or single point relay. For each group of ten tens relays there are ten units relays, or twenty relays in all for each 5 trunk. A group of this kind constituting one primary selector or dummy trunk terminal for thirty lines, is shown in Fig. 8, apart from the other figures, so as to free the lines from their multiple connections. 10 In order to make clear the connection of a line coming into the exchange, I will first refer to this figure and then trace the circuits through the others.

In Fig. 8, N , N' , N^2 , are three relays of 15 the type shown in Figs. 9 and 10, having ten pairs of contacts each for the line circuits. These relays correspond to the relays shown in Figs. 2 and 3, correspondingly lettered. At the top of the figure I have shown 20 the terminal ends of lines 500 to 529, inclusive, connected to a pair of contacts, n^3 , n^5 , such as shown in the mechanical figures 9 and 10. For lines 500 to 509 these terminals are in the relay N . For lines 510 to 519 25 they are in the relay N' . For lines 520 to 529 they are in the relay N^2 . Thus each relay contains line-terminals, n^3 , n^5 , for ten lines. When any one of the lines appropriated to a particular relay is calling, the 30 electromagnet, n' , of that relay becomes energized. This will be explained in connection with the circuits of Figs. 1 and 2 farther on. For example, if any line from 500 to 509 originates a call, the magnet, n' , of the relay, N , will become energized, and simultaneously connect all of the lines from 500 to 509 onto the extensions 10 to 19, inclusive. If, however, the calling line is in the group from 510 to 519, the magnet, n' , 35 of the relay, N' , will become energized, connecting all that group onto the extensions 10 to 19, inclusive. Similarly, if the calling line be in the third group, from 520 to 529, the magnet, n' , of the relay N^2 will be energized, connecting that entire group onto the 40 extensions 10 to 19, inclusive. Thus extensions 10 to 19 are seen to be common to all of the tens relays, and in fact each extension pair is multiplied to corresponding contacts in all of the tens relays. No. 10 extension goes to the first pair of contacts, n^4 , n^6 , in each of the relays, N , N' , N^2 . Extension No. 11 is multiplied to the second pair of contacts, n^4 , n^6 , in each of the relays, and 45 so on with all the extensions up to No. 19.

At the lower edge of Fig. 8, I have shown ten units relays, marked P to P^9 , inclusive. These are the same as the relays in Fig. 4, similarly marked. Each is a simple standard relay, of the type in common use, and preferably of the same general type as that shown in Figs. 9 and 10, hereof, viz., that type in which the electromagnet is mounted horizontally on a frame or rack, carrying 50 the contact springs upon it, and the whole

is inclosed within a dust-proof shell. Each relay has an armature, p^2 , adapted to be actuated by an electromagnet, p' , to close together the contacts, p^3 , p^4 , and p^5 , p^6 . In the present instance, that is in the trunk group of each primary selector, all of the contacts, p^3 , p^6 of the entire set of relays, P to P^9 , are connected together, forming a set of double parallel branches marked 20 to 29, inclusive, which are really so many open bridges 55 across the trunk circuit, 30—31.

The outfit shown in Fig. 8 is sufficient for 60 30 lines and by its use any one of the lines, 500 to 529, may connect itself to the trunk 30—31, by merely closing its line-circuit, and energizing the appropriate tens and units relays. The energizing circuits are not shown in Fig. 8, but will be described 65 in connection with Figs. 2, 3 and 4. They comprise parallel branches closed by the line-relay of each line when calling, one branch going to the appropriate tens relay, and the other branch going to the appropriate units relay, which thus became energized simultaneously and act in conjunction 70 to connect that particular line and no other to the trunk. For example, suppose line No. 512 is calling, the subscriber having taken 75 down his receiver from the hook, so as to close his line-circuit similar to the ones shown in Fig. 1, and energized his line-relay, M^{12} , shown in Fig. 3. This line-relay closes 80 two branches, one leading to the tens relay, N' , in Fig. 8, and the other leading to the units relay, P^2 , which is the third in the set 85 of ten. The actuation of the tens relay, N' , connects all of the lines 510 to 519 onto the extensions 10 to 19, inclusive; but it will be observed that these extensions are open 90 everywhere else, hence no effect is produced by this action alone. The third units relay, P^2 , however, connects the third extension 12 to the trunk 30—31, through the branch 22, and by following the circuits in Fig. 8 it will be found that this connects the line 512 95 onto the trunk direct, whereupon the trunk relays become energized, and further proceedings may be had. Only one line is thus connected to the trunk at a time, assuming of course that only one tens relay and one 100 units relay of the same set be energized simultaneously. It is true that the tens relay connects all of its lines onto the extensions; but all of these extensions are open 105 except the particular one which is closed 110 onto the trunk by the particular units relay energized. It is also true that the extension thus connected to the trunk is multiplied to the corresponding pair of contacts in every one of the tens relays, but this produces no 115 effect, because all but one of the tens relays remain deenergized.

Before passing from Fig. 8 it is necessary 120 to call attention to the fact that only three tens relays are there shown, accommodating 130

thirty lines. This limitation is due to the necessary limitations of a Patent Office drawing, and it is to be understood that the same principles apply to any desired group 5 up to 100 or more. It is most convenient in a scheme like this to make use of the decimal system, using ten relays per trunk, ten lines per relay, and ten trunk multiples per line. For 10 lines there would be ten of the tens relays, N, N', N^2 , etc., but still only ten of the units relays, and each of the extensions 10 to 19, inclusive, instead of being multiplied three times, would be multiplied ten times, into all the tens relays.

15 Turning now to Figs. 2, 3 and 4 we have here the same relays described in connection with Fig. 8, but somewhat differently arranged. Only two tens relays and three units relays of each set or of each trunk are 20 shown. I have assumed the numbers 500, 501, and 502 for the lines entering Fig. 2, and 510, 511 and 512 for the lines entering Fig. 3. The first three lines being within 25 the same tens digits of each other go onto the same tens relays in each set. For the sake of convenience I have given the designating numerals of the relays coefficients, and have marked the three trunks in Figs. 4 and 5 so as to be readily followed. Thus in 30 Fig. 2 all three of the lines come into the relay N , which is adapted to put them onto the extensions 10, 11, 12, etc., leading to the units relays, P, P', P^2 , etc., in Fig. 4. (I should here remark that the tens relays in 35 Figs. 2 and 3 are not shown with their full complements of springs, for the sake of simplicity.) Each of the lines 500, 501 and 502 not only terminates in contacts of the relay, N , but is multiplied to similar contacts 40 in the relays $1N, 2N$, etc. There would be one of these added for each trunk, that is appropriated to the group of lines. In the present case I only illustrate three trunks, so that each line need be multiplied only 45 three times.

In Fig. 3, the lines 510, 511 and 512 are connected to the tens relays, $N', 1N'$ and $2N'$ in the same manner as the lines in Fig. 2, each line being multiplied three times so 50 that each may have access to any one of the three trunks. It will be understood of course that the relays, N, N' , of Figs. 2 and 3, and P, P', P^2 , of Fig. 4, constitute one set, appropriated to the trunk 30—31, and 55 have precisely the same relation among themselves and the same connections, as the set shown in Fig. 8. Similarly the relays $1N, 1N', 1P, 1P', 1P^2$ all belong to one set, appropriated to the trunk-line 130—131. 60 Similarly again, the relays $2N, 2N', 2P, 2P'$ and $2P^2$ belong to one set, appropriated to the trunk-line 230—231. The extensions from the tens relays to the units are marked 10, 11, 12 for the first set, 110, 111, and 112 for the second set, and 210, 211 and 212 for 65 the third set. As these of course bear a logical relation throughout, and follow the same arrangement as that in Fig. 8, it is thought no difficulty will be experienced in comprehending the meaning of Figs. 2, 3 70 and 4. If Fig. 8 is understood, the description of the other figures may be put into one sentence. They show several groups like Fig. 8, with the line-wires multiplied to each group instead of terminating as in 75 Fig. 8 in single pairs of contacts.

The actual connection controlled by the relays N and P being thus understood, it is most important to explain the means by which I control these relays. Referring to 80 Fig. 2, the line-wires 1 and 2 terminate as I have stated, in the contacts of the cut-off relay M' ; through which they are normally connected to the line-relay M and ground. When the subscriber at station A^2 takes the 85 telephone from the hook, he closes his line-circuit, the line-relay M is energized, and the two branch circuits 50 and 51 are immediately closed. The branch 50 passes in 90 multiple to one winding of each of the three tens relays, $N, 1N$ and $2N$, these relays being double wound for the purpose of making them self-locking when attracted. Any one of these relays might thus be energized by any one of the three lines shown, but it is 95 my purpose that only one of them shall be so energized at once, and that no two lines shall be able to energize the same relay at the same time. Hence, on the other side of these relays I take away the circuit-wires, 100 which were designated generically by the numerals 54, 55 and 56, to three separate controlling means in the shape of special relays associated with the switch trunks. Each of the first named relays has its locking coil open on one side, but adapted to be 105 grounded by the relay itself in pulling up; and on the other side of this second or locking winding it is connected through one of the wires indicated by 57, 58, or 59, to controlling means similar to those I have just mentioned and which will also be specified later. The second branch from the line relay is marked 51 for line 502; 52 for line 501; and 53 for line 500. In other words, 110 each of these lines has its own units wire, as will be apparent at once if Fig. 8 has been understood. The three wires, 51, 52, and 53, pass along the bottom of Figs. 2 and 3 and into Fig. 4, where they terminate 115 in the first or operating windings of the three relays, P, P' and P^2 , also by multiples in the corresponding windings of the relays, $1P, 1P', 1P^2$ and $2P, 2P'$ and $2P^2$. The three relays, P, P' and P^2 , since they belong to the same set, have a common control, their return wires (of the set 54) 120 marked 54, 54^a and 54^b, passing to contacts 125

in a twenty-pair relay D^x . This relay controls the return wires of both the tens and units relays of this set, twenty in all. I find it advisable to have a relay provided with 5 separate terminal contacts for each of the wires 54^a , 54^b , etc., in each set 54 , 55 or 56 , because of certain complications which arise when battery is put on without any resistance, the working then being on a margin 10 which is too narrow to be called absolute. In other words, when the controlling relay for any set has cut off the return wires from the actuating windings of the tens and units relays, they are all separated from each 15 other and as those of one trunk only are closed together at any one time, the separation of the relays associated with the other trunks prevents the formation of any parallel paths when a line calls.

20 Each of the units relays in Fig. 4 has a locking winding separated from the actuating winding and each locking winding terminates on one side in a contact normally open but adapted to be grounded when the 25 relay is energized. All the locking windings of the first set or group have a common return, 61 , passing onto the wire 57 , which is the control wire of the locking windings on the tens relays, N , N' . This wire 57 30 passes into Fig. 5 and is there carried to a pair of the trunk relays by which it is controlled. The actuating windings of the units relays, $1P$, $1P'$, and $1P^2$, have return wires generically indicated by the numerals 35 62 , (and individually as 62^a , 62^b , etc.), passing to the contacts of the relay $1D^x$ (of Fig. 5) associated with the trunk $130-131$. The locking windings of these relays have a common return 63 , which goes to the wire 40 58 , passing into Fig. 5 and there controlled by one of the trunk relays in the same manner as in the first set. Similarly, the actuating and locking windings respectively, of the units relays $2P$, $2P'$ and $2P^2$, have their 45 return wires passing into Fig. 5 and there controlled by relays associated with the trunk.

It is thought the scheme will now be plain. Suppose that one of the line-relays, as that 50 of line No. 502 , pulls up. It grounds the local circuits 50 and 51 and energizes whichever one of the ten relays, N , $1N$ or $2N$ happens to be eligible, together with the appropriate units relay. This would be one of the three 55 relays, P^2 , $1P^2$, or $2P^2$ in Fig. 4. The tens relay and units relay thus selected having pulled up, their locking windings are grounded, and hence they are maintained energized through the locking common return wire as long as a subscriber keeps his receiver off the hook, being finally deprived of current when the subscriber hangs up, so 60 that the relays are then restored. I have thus shown, first, a single trunk group of

primary selector relays, and second three 65 such groups, or at least portions of three groups, belonging to three several trunks, and having the subscribers' lines connected to them in multiple. I will now point out how a calling line is permitted to select an 70 idle trunk only, by working idle relays only. For this purpose it is necessary that I should refer briefly to Fig. 5. This figure shows portions of a trunk circuit, each of 75 which commences on the left of the figure, which is supposed to be the terminal point of attachment of the selective set shown in the preceding figures and in Fig. 8.

The three trunks are marked respectively 80 $30-31$, $130-131$ and $230-231$. Each of them is divided by condensers C so that the portions to the right of the condensers in the figure can be used for sending direct current out through the switches without interfering with the incoming call end. I have 85 designated the outgoing or switching end of the trunk as 30^x-31^x , etc. Across the incoming or answering end of each trunk is bridged a pair of relays D , D' , $1D$, $1D'$, or $2D$, $2D'$, each with the main battery B between them. This battery is grounded as usual on its positive bus, and when the primary selector set first puts a call on one of the trunks, as $30-31$, its sleeve relay D' will 90 immediately pull up in series with the cut-off relay of the calling line. The incoming end of the trunk, therefore, corresponds to the answering cord circuit of an ordinary manual system, the primary selector set performing the same functions as the answering plug and jack; hence, the battery supply for talking as well as for signaling over the calling line is drawn through two relays D , D' . D' being the sleeve side relay, remains energized as long as the primary 95 selector set is on. The relay, D , on the other hand responds to the subscriber's acts, being energized by current coming over the subscriber's line, and therefore controlled by his switch-hook. It will be observed in the 100 switching end of the three trunks shown in this Fig. 5, that in each instance there is a relay, E^x , which is normally deenergized, but becomes energized when the calling plug is inserted in a trunk jack leading to an 105 idle connector switch. I run the common wire 57 or 59 from the locking windings of all the primary selector relays of each trunk to a back contact on the relay E^x , this contact being normally closed upon main battery B . These relays are all energized when the switching is done, but they serve normally to keep current on the locking wires, so that when any set of relays pulls up it 110 will be enabled to lock instantly, even before the tip relay D of the trunk has pulled up. When this latter relay becomes energized, 115 it takes control of the locking wire in every 120 125

case, and since the signaling relays are all locked up during a connection, the relay D alone controls the locking windings, and releases the same to clear out when the calling subscriber hangs up his telephone.

Having thus shown that the locking windings are all maintained active, it remains to point out how the actuating windings of the different selective relay sets are rendered

- 10 active one at a time. This is by means of the relays D', D*. In Fig. 5 it is assumed that the lowermost trunk is No. 1, the next above is No. 2 and the uppermost trunk, 30—31 is No. 3, in the order of their becoming busy. The instant a call comes in and is put on the lower trunk, 230—231, its sleeve relay 2D' is pulled up and puts battery on the relay, 2D*. This latter relay is normally deenergized, and the actuating 20 windings of the various tens and units relays belonging to its trunk are therefore normally closed onto battery through the wires 56^a, 56^b, 56^c, 56^d, 56^e, etc.; there being twenty relays to the trunk and hence twenty 25 wires for the actuating windings, I employ a ten-pair relay of the type shown in Figs. 9 and 10, at the point, 2D*. Of course the springs on this relay may be arranged to either open or close the respective circuits 30 when the relay is energized, as the case may be. The relay 2D* of the first trunk must open these circuits. Succeeding relays must leave them normally open and when energized must close them. In other words, as 35 I have illustrated them in the drawings, the first relay 2D* is normally closed when deenergized, but all the rest of the relays in the series, as 1D* are normally opened when deenergized, so that the relay selector of 40 the first or lower-most trunk is in condition to get current at once and hence will take the first call. As soon as this call is placed on the trunk, the relay 2D' puts battery on the wire 14 leading to the armature of the 45 relay 1D' of the next trunk, which normally completes the circuit of the relay 1D*. The latter becoming energized immediately closes battery onto the actuating windings of the relay primary selector set of its trunk, 50 which thereupon become sensitive and in condition to take the next call; and so on to succeeding trunks. I have shown only five contacts on each of the controlling relays, for the sake of simplicity in illustration, but it will be understood that there 55 may be as many as are required. The relay D when energized closes the circuit of the signal lamp r' through the normally closed contacts of the relay E*. The relay E* is 60 energized in series with the resistance coil I' when the plug P is inserted in the jack J. The energizing of this relay opens the circuit of and extinguishes the lamp r'. The relay E* when energized connects one ter-

65 minal of the lamp r to ground and when the relay D' falls back the other terminal of this lamp is connected to battery causing it to glow, notifying the operator that the calling party has hung up his receiver. The wires 15 and 16 connected to the tip and 70 sleeve of the plug P lead to a set of buttons which control impulses from a sending machine.

In Fig. 6, Q⁰, Q, Q', Q², Q³, Q⁴, Q⁵, etc., are a set of wheels mounted on and turning 75 with a common shaft, which may be driven in any suitable manner. The wheel Q⁰, puts battery and ground alternately on the wire 29, which for purposes of illustration represents the metallic shaft connection between the wheels. The wheel Q is insulated from the shaft and is grounded and has an insulating spot in its periphery, and controls by means of this spot the locking and unlocking wires 30 and 31, in a manner 80 which will appear from the statement of operation. The wheels Q', Q², Q³, Q⁴, Q⁵, etc., are number wheels, the first one having one tooth, the second two teeth and so on up to ten teeth. (For simplicity of illustration 85 only five wheels are shown). Around these wheels are three sets of pens, connected to the three sets of keys K', K², K³. As the wheels revolve from the position in which they are shown in the figure, they first make 90 connection with the upper pens q', then with the pens q², then with those of q³. The first set with their buttons or keys, K', transmit the tens digit of any number, the next set 95 transmit the units digit, and the third set 100 transmit the ringing number for party-line work. All this will appear more clearly from the statement of operation.

The keys, K', K², K³ are of the so-called self-latching selective ringing type now in 105 common use on manual switchboards, and employ the principle shown in the patent to Ham, No. 605,097 granted June 7, 1898. When any key is pressed down it pushes back the latch and releases the one that was 110 previously down, then latching itself. Each set of keys has a common wire, this for the sets K', K², being marked 32, these two being joined together and carried to a back contact of the relay R⁴, while that for the set 115 K³ is marked 33 and carried to another back contact of the same relay, separately controlled. The numbers to be sent are set up by depressing the keys, and then the signal is started at the beginning of a rotation 120 of the shaft, when the first tooth of each wheel is about to strike its pen q', by the relay, R⁴, being deenergized, while the relay R⁵ remains energized. The trick of this is in the arrangement of the spring pens q⁵, q⁶, 125 on the wheel Q. This wheel is rotated with the others in the direction of the arrow, and its insulating spot passes first under the

spring pen q^5 , momentarily cutting ground off of that and the wire 31, then under the pen q^6 , taking ground off of that.

It will be noted that the bank of keys is divided into three sets or rows, K' , K^2 and K^3 respectively. The rows are each provided with the latching device of Ham, cited, the rows being independent of each other in this respect; thus one key and only one of each row will remain depressed, the previously depressed key of each row being released by the depression of any other. In a bank or row of keys of this nature, a key is depressed through a travel carrying it beyond the locking point; upon release it returns a very short distance and remains locked there until released by the depression of the next key used. I take advantage of this detail in the row of keys K^3 in the following manner: The pairs of springs as k^4 are to remain locked when the key is pressed, as described later, but the triple springs k^6 are springs requiring but a momentary contact to energize primarily the pair of locking relays R^4 , R^5 . To secure the desired end, I so gage the relation of the springs k^6 to the push button of the key that they are closed by the button when at its point of farthest travel but are released by the slight return travel of the button before it is locked. The springs k^4 however remain closed until the button is unlocked and fully released.

In calling the number wanted which we will assume to be 32-3, the operator plugs into the calling jack, then presses down button No. 3 of the set K' ; No. 2 of the set, K^2 , and No. 3 of the set K^3 . The buttons of the sets K' and K^2 have their several individual wires connected to the pens on the several individual wheels Q' , Q^2 , etc., and the effect of pressing down the buttons as mentioned is to connect the pen of the wheel Q^3 through the springs k' of the button K to the wire 32. At the same time the pen q^2 of the wheel Q^2 is connected through the springs k^3 of the button k^2 to the wire 33 and the spring q^3 of the wheel Q^3 is connected through the springs k^4 of the button k^3 to the wire 32. The set of buttons K^3 , also have what I may call starting springs k^6 . This set of buttons being the last, or ringing set, the number is ready for transmission when any one of them is depressed, hence any one of these buttons not only finishes setting up the number, but by closing the springs k^6 puts ground on the starting wires 37 and 38, which pass to the two relays R^4 , R^5 , respectively, and thence through the common return wire 39 to battery B and ground. Both the relays pull up, and both lock, the locking circuit of the relay R^4 being as follows: B, 39, R^4 , r^4 , 30, q^6 , Q and ground. The locking circuit of R^5 is as

follows: B, 39, R^5 , r^5 , 31, q^5 , Q and ground. Having thus set up the signal and put it in condition to be started at the beginning of a revolution of the main shaft, and having also plugged into the necessary hundreds group, the operator's work is finished. She pays no further attention to the connection until the subscribers have completed their conversation and have hung up, whereupon the relay D releases its armature, breaking the locking circuit of the relays of the primary selector; by the release of the primary selector relays, the connection between the relay D' and the cut-off relay of the calling line is interrupted, the relay D' releases its armature, and the lamp r lights to call for disconnection. The operator then pulls the plug P.

The signal having been set up as described, the apparatus of Fig. 6 then operates as follows: The wheel, Q, in revolving will bring the insulating spot under the pen q^5 at first, and might thereby cut off the relay R^5 prematurely, but this is provided for by making a branch locking circuit 310 which is controlled through a contact of the armature r^6 and a ground wire 36 of the starting relay R^4 . Hence, as long as the relay R^4 is energized, the relay R^5 cannot be affected. Moreover, it will be observed that the wires 32 and 33 remain disconnected from the wires 15-16 until the relay R^5 is energized, while the relay R^4 is deenergized. This condition is brought about when the insulating spot reaches the pen q^6 . The relay R^4 then lets go, and we have a continuous circuit from wire 32 as follows: 32, r^4 , 34, r^3 , 16, (in Fig. 5), and to trunk wire 114. We also have a circuit from wire 33 as follows: 33, r^2 , 35, r^4 , 15, (Fig. 5) and the other trunk wire 113. The insulating spot reaches the pen q^6 just before the first tooth on each wheel reaches its pen, q' ; hence as soon as the above desired condition is attained, the set of impulses which has been determined by the key k of the set K' , comes from battery over the wire 32 to the wire 16 and so onto the wire 114 of the trunk, through which it passes into Fig. 7 to the relay R^6 which will be presently described, and which I shall call for convenience the vertical relay. At the end of this group of impulses, the teeth on the wheels will have gotten around to the pens q^2 and so the next group of impulses determined by the key k^2 will pass from ground onto the wire 33 and so to the wire 15 and the trunk wire 113, through which they reach the relay R^7 in Fig. 7 which will also be presently described and which I shall for convenience call the rotary relay. The names of these two relays are quite accurate in this system, because the relay R^6 does really produce a vertical motion of the switch

S, while the relay R⁷ produces a rotary motion thereof. At the end of this second group of impulses, the teeth on the wheels have gotten around to the third set of pens 5 q³ and the impulses determined by the key k⁵ then come from battery through the wire 32 onto the wire 16 and so again to the trunk wire 114 and to the vertical relay R⁶. After this, the insulating spot on 10 the wheel Q reaches the spring q⁵ and momentarily cuts off the ground therefrom. Since the relay R⁴ is already deenergized, this breaks the locking circuit of the relay R⁵ and it lets go, disconnecting the wires 15 15—16 from the wires 30^x—31^x, and leaving the apparatus free for another operation.

Referring now to Fig. 7, I will briefly describe the switch operation. The switch spindle controls a pair of springs s⁵ which 20 it opens when it is down in its normal position of disuse, for restoring purposes, as will presently appear. s⁶ is the release magnet of the switch, which when energized removes the detent pawls from the respective 25 ratchets of the spindle, s, allowing the spindle to drop down and rotate back to zero, as fully described in the Patents 815,176 and 815,321, both of March 13, 1906, to Keith *et al.* This release magnet is under 30 the control of the relay R¹⁰ which in turn is controlled by the relays R⁶ and R⁷. It is also under the control of the test relay R¹¹. R¹² is a ringing control relay, R¹³ is a trunk cut-off relay and R¹⁴ is a ringing relay controlled 35 by the commutator X which is common to the entire exchange. R¹⁵ is a slow acting relay, preferably a solenoid, which connects the test relay R¹¹, at the moment of effecting connection, as controlled by the 40 first ringing impulse, and at the same time opens the generator circuit 140—141, while the proper current is being selected. R¹⁶ to R²¹, inclusive, are selective relays for enabling one or the other of the ringing generators, G, G', G² and G³, to be connected onto the ringing contacts of the ringing relay, R¹⁴, the particular generator being determined by the number of impulses received through the relay R¹² which operates 45 50 the relays R¹⁶, R¹⁹, etc., in succession, each of them locking as it operates.

The operation of this trunk scheme is as follows: In selecting the number we have assumed 32-3: (the trunk itself corresponds 55 to the hundreds number, if such there be) we have first three impulses from battery over the wire 114 to the relay R⁶, then two impulses from ground over the wire 113 to the relay R⁷, and then three impulses from 60 battery over the wire 114 to the relay R⁶. The first three impulses coming over the wire 114 causes the relay R⁶ to pull up three times, each time closing the following circuit; B, 142, 143, 144, s³, 145, 146, 147, 65 and ground to battery. The vertical magnet

s³ steps the spindle s of the switch up three steps, so that the wipers s' stand opposite the third row of contacts. Two impulses then come over wire 113 affecting the relay R⁷ which pulls up twice, the first time closing the following circuit: B, 142, R⁹, 149, armature of R⁷, armature of R¹⁰, 151, to ground and to battery. The relay R⁹ instantly pulls up, cutting off the vertical magnet, s³, and locking itself by the following path: B, 142, 70 R⁹, r⁹, 152, 151 and ground back to battery. The vertical magnet s³ is therefore cut off for the rest of the transmission. The rotary magnet s⁴, however, gets current each time the relay R⁷, is energized, over the following path: B, 142, 143, 144, s⁴, armature of 75 relay R⁷, 154, 155 and ground back to battery. The rotary magnet s⁴ turns the spindle s two steps, so that the wipers s' rest on the second pair of contacts in the third row, or No. 32. Three impulses now come over the wire 114, causing the relay R⁶ again to pull up three times. Each time it closes the following local circuit: B, 142, R¹², 157, 146, 147, and ground back to battery. As a 80 branch of this same circuit, the wire 158 comes in from battery wire 142, through the solenoid R¹⁵ and goes to 157, 146, 147 and ground. At this point in the development of the connection immediately following the 85 closure of the contacts of relay R⁶ at the beginning of the first generator-selection impulse, two things occur simultaneously:

(1) The solenoid R¹⁵ attracts its core, 90 opening the wires 140—141 and closing the switch 162 whereby a test circuit is formed through elements B, 142, 162, R¹¹, 163 to upper s', which at this moment is resting in contact with the line selected through the agency of vertical and rotary magnets s³ s⁴; 95 if the line be busy because it is calling, then a circuit will exist from upper wiper s' through the line multiples to the tip side of the other trunk used in answering, and, through the relay D of that trunk to ground; while if the line is busy because it has previously been called then the test circuit will continue through the line multiples to the wiper s' of the other switch used in calling the line, thence through the other trunking equipment following a path corresponding to contact of R¹⁴, contact of R¹³, conductor 114 and winding of R⁶ to ground; in either case the test relay R¹¹ will be energized and in turn will energize the release magnet s⁶. 100 If, however, the selected line with which the test wiper rests in contact is not busy, no circuit will exist from that test wiper to ground and the test relay R¹¹ will not be energized; a branch path for the conductor 163 exists 105 through the talking conductor of the trunk to the left hand contact of relay R¹⁴ and thence to an armature contact of relay R¹³ where it terminates open, but subsequent to the energization of relay R¹⁴ as about to be 110 115 120 125 130

described, this branch path passes to the inner contact of the left hand armature of that relay and thence over the conductor 141 to the right hand switch of the solenoid R^{15} which during the test period is open, and thus test relay R^{11} has its circuit open at all points and the design of the device as a whole is that no energization of that relay may result when the line selected is in a condition of disuse and subject to use in the connection now being established.

(2) The relay R^{12} is energized over the path B, 142, R^{12} , 157, 146, 147 and ground. By the closure of the left hand armature of relay R^{12} , circuit is formed through elements B, 142, 156, armature of R^{12} , 160, winding of R^{13} , 161, switch s^5 and ground, energizing relay R^{13} which locks itself energized over the circuit B, 142, 143, armature and inner contact of relay R^{12} , winding of relay R^{13} , 161, s^5 and ground. This energization of trunk-connecting relay R^{13} connects the conductors 114—113 of the trunk through to the outer contacts of the ringing relay R^{14} and through to the wipers s' . This furnishes a path through test relay R^{11} as follows: B, 142, 162, R^{11} , 163, talking conductor to left hand armature of R^{14} , back contact and talking conductor to armature of energized relay R^{13} , conductor 114, winding of relay R^6 and ground; however, this circuit is adapted to be opened by the attraction of the armatures of relay R^{14} and it is the function of the connector switch 35 that the opening of this circuit at R^{14} shall succeed its closing at R^{12} by a time limit so small that restoration of the connector switch is not permitted. It will be noted in the study of this time element that the 40 test relay R^{11} must attain the degree of magnetization required to attract its armature, must swing its armature through its full travel to close its contact, and that subsequently to the closure of the contact of R^{11} the release magnet s^6 must reach its required 45 degree of magnetization and must overcome the inertia of its armature and move it through some definite arc before release of the switch will be effected; this series of necessarily consecutive operations limits the 50 duration of the momentary false test here considered. The commutator X is carried upon the shaft which carries the number wheels and commutator devices Q^a, Q, Q', Q^b, etc., and the commutator X is adjusted 55 angularly with respect to those wheels so that the conducting portion of X is in electrical connection with its brush at the time that the energization of relay R^{12} occurs. It is seen therefore that by the closing of the 60 contacts of relay R^{12} , by which current flow through test relay R^{11} was permitted, current flow also was simultaneously provided for through the path B, 142, X, winding of 65 R^{14} , contact and armature of R^{13} , 168, R^{10} , 151

and ground. Thus current begins to flow through the winding of relay R^{14} at the same instant that current begins to flow through the winding of relay R^{11} , and, assuming equal speed in the operation of armatures, relay R^{14} will have moved its armature and will have broken its back contact, thereby cutting off current from relay R^{11} , in ample time to prevent the restoration of the switch S by operation of release magnet s^6 , the 70 break at the armature of R^{14} probably occurring in time to prevent any contact whatever at the armature of relay R^{11} . Thus a test condition is maintained with the test wiper s' isolated from the winding of relay R^6 by the break at the armature of relay R^{14} , and the design and adjustment of the commutator X shall be such that the relay R^{14} is held energized through the maximum period occupied by generator-selection impulses and until the opening of the circuit of the test relay R^{11} by the opening of the switch 162 upon release of the armature of the solenoid R^{15} . The armature of the solenoid R^{15} is sluggish and does not open the 80 switch 162 between the generator-selection impulses, so that the test circuit here described is maintained continuously during the period of generator-selection.

Leaving the various parts of apparatus in 95 the condition now considered, we will follow the action of the apparatus in response to the generator-selection impulses. In the instance assumed, since station No. 3 is to be called three battery impulses will be received over the wire 114 operating the armature of the relay R^6 successively three times, which in turn acts over the path 147, 146, 157, R^{12} , etc., to operate the armatures of relay R^{12} in succession three times; the 100 armature r^{12} through its front and back contacts effects the selection of the desired ringing generator as follows: Upon attraction of r^{12} by the first generator-selection impulse, it makes electrical connection with its 105 inner contact, but inasmuch as the wire 164 is open at the armature of relay R^{10} no complete circuit is closed. Upon the release of the armature r^{12} at cessation of the first generator-selection impulse, circuit is closed 110 through elements B, 142, 143, contact of R^{13} , 160, r^{12} , 165, contact of R^{16} , winding of R^{19} and ground, energizing relay R^{19} which locks over the circuits B, 142, 143, contact of R^{13} , 160, 169, armature and contact of R^{19} , winding of R^{19} and ground. If 115 but one generator-selection impulse were received, the generator G' would remain in connection with conductor 140 ready for connection through conductor 141 to the 120 ringing relay R^{14} . At the beginning of the second generator-selection impulse, relay R^6 is energized and armature r^{12} is attracted, closing circuit through elements B, 142, 143, contact of R^{13} , 160, r^{12} , 164, closed contact 125 130

of lower armature of relay R^{19} , back contact of unenergized relay R^{20} , winding of relay R^{16} and ground, energizing relay R^{16} which then locks over the circuit B, 142, 143, contact of R^{13} , 160, 169, armature contact and winding of R^{16} . Upon the cessation of the second generator-selection impulse, the armature r^{12} is released, closing circuit over B, 142, 143, contact of R^{13} , 160, r^{12} , 165, closed contact of lower armature of energized relay R^{16} , back contact of lower armature of unenergized relay R^{17} , winding of relay R^{20} and ground, energizing relay R^{20} , which then locks itself through its own contact by current received over conductor 169 to ground as in the case of relays R^{16} and R^{18} . If no more generator-selection impulses were received, the effect of the two impulses thus far followed would be to leave generator G connected to conductor 140 through contact of energized relay R^{16} , that being the proper generator for ringing the second station on a party line. At the beginning of the third and last generator-selection impulse, the armature r^{12} is again attracted, closing circuit over elements B, 142, 143, contact of R^{13} , 160, r^{12} , 164, closed contact of energized relay R^{19} , closed inner contact of energized relay R^{20} , closed outer contact of unenergized relay R^{21} , winding of relay R^{17} and ground, energizing relay R^{17} , which then locks itself by current through its own contact and winding over conductor 169 to ground. Upon the cessation of the third and last generator-selection impulse, the armature r^{12} is released, closing circuit through elements B, 142, 143, contact of R^{13} , 160, r^{12} , 165, closed inner contacts of energized relays R^{16} and R^{17} closed outer contact of unenergized relay R^{21} , winding of relay R^{21} and ground, energizing relay R^{21} which then locks itself by current through its own armature contact and winding from conductor 169 to ground. This leaves relays R^{16} and R^{17} energized and leaves relays R^{18} unenergized, thus effecting the connection of generator G² to the conductor 140, and as the generator-selection impulses now cease, solenoid R^{15} releases its armature, opening the circuit of the test relay R^{11} and closing the circuit between conductors 140—141, thus connecting the selected generator G² over conductor 141 to the inner contact of the left hand armature of ringing relay R^{14} and thus through the upper wiper s' and to the line conductor of the selected line to ring the third station upon the party line selected. The ringing will continue until the insulated portion of the commutator X passes under the brush of that commutator when the circuit of the winding of relay R^{14} will be interrupted and by release of that relay's armature the circuit from the wipers s' will be removed from the generator and carried to relays R^7 and

R^6 respectively. The line selected will be subjected alternately to periods of ringing when the relay R^{14} is energized and to periods of non-ringing when the relay R^{14} is deenergized. Upon the answering of the 70 called sub-station, or of any sub-station upon that party line, during a period of non-ringing, current immediately will flow through elements B, 142, winding of R^7 , 113, lower s' , line conductor, substation bridge, 75 return line conductor, upper s' , 114, winding of R^6 and earth, energizing R^6 and attracting its armatures.

By the operation of the left hand armature of R^6 , circuit is closed through elements B, 80 142, left hand armature and inner contact of R^6 , winding of R^{10} , 154, contact and left hand armature of R^7 , 155 and ground, energizing R^{10} which then locks over the circuit B, 142, right hand armature and contact of 85 R^{10} to winding of R^{10} , 154, contact and armature of R^7 , 155 and ground. By energization of relay R^{10} , ground is taken off of wire 152 so that ringing relay R^{14} may not again be energized. Also by the energization and 90 locking of R^{10} the relay R^6 is released and remains released throughout the remainder of the connection. This is the condition of conversation and continues until the hanging up of the telephone and the breaking of the 95 substation bridge upon the called line. Upon the hanging up of the telephone and the breaking of the substation bridge upon the called line, disconnection of the switch is effected as follows: Circuit is interrupted 100 over the return wire of the line and through relay R^6 to ground, releasing the armatures of relay R^6 , but current continues through elements B, 142, winding of R^7 , 113, lower wiper s' , and the sleeve side of the connected 105 line and the winding of its cut-off relay M' to ground, maintaining the energization of the relay R^7 . This will be apparent from an examination of Fig. 7 in connection with the line circuits in Fig. 2. The circuit from 110 R^7 to M' is closed through the line sleeve multiple and the wiper s' . By the release of the left hand armature of relay R^6 a release relay circuit is established through elements B, 142, left hand armature and outer 115 contact of deenergized relay R^6 , winding of release relay R^{22} , inner contact and armature r^{10} of relay R^{10} , 151 and ground, energizing release relay R^{22} which, by closing its contact, energizes release magnet s^6 , which effects immediate restoration of all parts of 120 the switch to the normal position of disuse.

A consideration of test conditions during the process of the connection is desirable. When the test wiper or upper wiper s' connects with the test conductor of the line, no action is taken either to test for busy or to place a busy test upon the line until the wheels Q', Q², Q³, etc., have in due course 125 of progress begun to send the generator-se- 130

lection impulses; at this time, by the action of the solenoid R^{15} , the selected line is tested for busy condition, the testing for busy being continued throughout the receipt of the generator-selection impulses and the line being left unguarded against connection by other connectors; at the close of the generator-selection impulses the test relay is taken off and the ringing generator is substituted. From this time a busy test guard condition is placed upon the test conductor of the selected line, being alternately the potential of the selected ringing generator when the relay R^{14} is energized, which is sufficient to energize any relay R^{11} which may test the line during the interval of ringing, and between the intervals of ringing the busy test consists of the ground circuit through the relay R^6 . If the line thus connected with the tested for busy by some other connector attempting a connection with it and during the interval of deenergization of ringing relay R^{14} , a current will flow from the connector then testing to the test conductor of the line, thence through the test wiper of the connector of Fig. 3 holding the line, and through back contact of relay R^{14} , front contact of R^{13} , 114 , and winding of R^6 to ground. This current will be of sufficient strength to energize the test relay R^{11} of the distant connector attempting to take the line being held, and this will effect disconnection of that connector but it will not be of sufficient strength to energize the relay R^6 inasmuch as by the energization and subsequent deenergization of that relay, the said testing current would also restore the holding connector of Fig. 3 to its normal condition of idleness. The relay D in Fig. 5 falls back when the calling party hangs up his receiver thus opening the locking wire 57 allowing the primary selector outfit to become disconnected. The relay D' falling back closes the circuit of the lamp r notifying the operator that the parties are through talking and she thereupon withdraws the plug from the trunk jack.

I have thus described my invention in one specific form for the purpose of rendering it clearly comprehensible, but it is to be understood that I do not limit myself to the specific form or arrangement described. I may vary the methods and matters described in many ways without departing from the spirit of the invention. I wish particularly to call attention to the fact that there are certain features of the invention which should not be limited to use merely in combination with others. Thus, those portions of the invention shown in Figs. 1 to 5, inclusive, are complete, and the connecting jacks J in Fig. 5 may well be the multiple jacks of line circuits, omitting the automatic switches entirely. In such case the apparatus in Fig. 6 would be superfluous, and the cord circuit would contain the ordinary operator's listen-

ing and ringing key. The same may be said as to completeness of that part of the invention embraced in Figs. 5 to 7, inclusive, the incoming trunk ends being then taken as lines merely. All minor changes and adaptations, as well as sub-combinations, I wish to include in the scope of my claims. 70

In the claims hereinafter I shall refer to B switches to indicate switching mechanism which is definitely directed or driven to select a particular line. The letter "B" is used as a convenient designation for this type of switch because it is one of the algebraic symbols for known quantities. 75

Having thus described my invention what I claim and desire to secure by Letters Patent is: 80

1. In a telephone exchange system, a plurality of line circuits to be interconnected, a plurality of terminal plugs less in number than the number of lines, and groups of relays associated with the respective plugs, each group common to a plurality of lines and containing terminal contacts thereof for connecting any line when calling to an idle terminal plug, together with automatic switching apparatus containing multiple terminals of the lines, and jacks forming terminals for the switch circuits, adapted to receive the plugs, whereby calls made over the lines will automatically distribute themselves upon the plugs, and the plug circuits may be trunked to automatic switches for the purpose of completing the connections desired. 90

2. In a telephone exchange system, a plurality of line circuits, a plurality of terminal plugs, groups of relays common to said lines, one group associated with each plug, for automatically connecting a calling line to an idle plug, a signal associated with each plug and becoming active when a calling line is connected thereto, and automatic switches co-operating with said plugs to complete the connections desired. 100

3. In a telephone exchange system, a plurality of lines to be interconnected, and connective apparatus therefor comprising the following instrumentalities; terminal plugs, primary selector switching relays in decimally arranged groups containing line terminals, one group associated with each plug, for connecting the calling lines with idle plugs, automatic switches and jack terminals therefor, together with manually operated controlling apparatus for the switches. 110

4. In a telephone exchange system, a plurality of lines to be interconnected, and connective apparatus therefor comprising the following instrumentalities; terminal plugs, primary selector switching relays in decimally arranged groups containing line terminals, one group associated with each plug, for connecting the calling lines with idle plugs, automatic switches and jack terminals 125

therefor, together with manually operated controlling apparatus for the switches associated with the plugs and adapted to be connected to the switches through the plugs and 5 jacks.

5. In a telephone exchange system, a plurality of line circuits to be interconnected, a plurality of single cord terminals less in number than the number of lines, jacks co-10 operating with the single cord terminals for completing connections desired, and relays interposed between the cord terminals and the lines in decimal relation with each other and containing multiples of the lines, where-15 by a calling line may be connected to an idle cord terminal.

6. In a telephone exchange system, a plurality of line circuits, a number of single cord terminals less than the number of lines, 20 groups of relays decimaly arranged, each group associated with a single cord and all the groups containing multiples of the lines, a selected pair of relays in each group responsive to each line when calling so as to 25 constitute switching apparatus for connecting the lines to idle terminals and coöperating terminals for completing the connections desired.

7. In a telephone exchange system, a plurality of line circuits to be interconnected, a 30 number of single cord terminals less than the number of lines, jacks coöperating with said cord terminals for completing connections desired, and magnetic switching apparatus interposed between the lines and cord terminals for distributing incoming calls over the cord terminals, said switching apparatus comprising decimaly arranged switching relays of the order of the units 35 digit identified with the individual lines of a number of groups, and other relays of the order of the tens digits identified each with a plurality of lines constituting a group.

8. In a telephone exchange system, a plurality of line circuits, a plurality of primary selector sets composed of groups of relays 45 common to the lines, each group containing line multiples, a single cord terminal for each primary selector set, and coöperating connection terminals.

9. In a telephone exchange system, a plurality of line circuits to be interconnected, a plurality of terminal plugs less in number than the number of lines, a primary selector 55 set composed of a group of interacting relays for each plug, said primary selector sets common to and containing multiples of the line circuits which they serve, and means adapted to be controlled over a line for ren-60 dering the primary selector sets in which the line has multiples active so as to connect with the line.

10. In a telephone exchange system, a plurality of line circuits to be intercon-

nected, a plurality of terminal plugs less in 65 number than the number of lines, a relay primary selector set for each plug, said primary selector sets containing multiples of line circuits, and line relays adapted to be controlled over a line for rendering the 70 primary selector sets in which the line has multiples active so as to connect with the line, and thereafter to disable the primary selector so that no other connection can be effected therethrough as long as the original 75 calling line is in use.

11. In a telephone exchange system, a plurality of line circuits to be interconnected, a plurality of primary selectors composed of relays and containing terminals of 80 the lines, a plurality of terminal plugs for the primary selectors, a calling signal associated with each plug, connecting jacks for the plugs, and means whereby the insertion of a plug in a jack to complete the connection desired will disable the calling signal.

12. In a telephone exchange system, a plurality of line circuits to be interconnected, a plurality of primary selectors composed of relays and containing terminals of 90 the lines, a plurality of terminal plugs for the primary selectors, a calling signal associated with each plug, connecting jacks for the plugs, and means whereby the insertion of a plug in a jack to complete the connection desired will disable the calling signal, 95 together with a clearing-out signal also associated with the plug, and brought into condition to be rendered active, when the plug is inserted in a jack.

13. In a telephone exchange system, a plurality of line circuits, a plurality of relay primary selectors less in number than the number of lines, a single plug terminal for each primary selector, a calling and a 100 clearing-out signal associated with each plug, a controlling relay for said signals also associated with the plug and becoming active when the latter is inserted in a calling jack, and cord circuit relays brought under 110 control of a calling line through the relay primary selector and thereafter controlling the calling and clearing-out signals in sequence.

14. In a telephone system, a plurality of 115 telephone lines; a link circuit; a constantly revolving generator of signal impulses; automatic B-switches, automatic means for connecting said link to a calling line; manual means for connecting said link to said generator of signal impulses; and further 120 manual means for connecting said link to an automatic B-switch.

15. In a telephone system, a plurality of 125 telephone lines; a link circuit; a constantly revolving generator for signal impulses; a mechanical number selecting device associated with said link; automatic means for

connecting said link to a calling one of said telephone lines; automatic B switches; manual means for connecting said link to one of said automatic B-switches; and further means for connecting said link to said signal impulse device through said number selecting device, whereby said generator may operate said B-switch in accordance with

the number set up upon said number selecting device.

In testimony whereof I affix my signature ¹⁰ in presence of two witnesses.

EDWARD E. CLEMENT.
